Attorney

UNITED STATES PATENT OFFICE

WILLIAM A. HARTY, OF BUFFALO, NEW YORK, AND FRANK W. MOORE, OF THOROLD, ONTARIO, CANADA, ASSIGNEES TO HARMOR & CO. INC., OF BUFFALO, NEW YORK, A CORPORATION OF NEW YORK

DRIER

Application filed May 26, 1930. Serial No. 455,602.

This invention is a continuation in part of our prior application, Serial No. 228,212, to which reference is made as containing a general discussion of the installation and maintenance problems presented in drying material with a rotary drier of the hot mandrel type wherein the mandrel and shell rotate in unison and the drying heat is projected into one end of the mandrel.

10 Our present invention contemplates certain improvements upon the drier disclosed in said prior application, particularly in respect to the means for supporting the mandrel within the shell to rotate therewith while at the same time compensating for the expanding and contracting movements of the mandrel, due to temperature changes.

15 The mandrel expands and contracts both radially and longitudinally and the means which mount the mandrel in the shell in spaced relation thereto must not only serve to transmit the rotary effect of the shell to the mandrel but must also automatically take up the longitudinal and radial expanding and contracting movements of the mandrel relative to the shell.

20 Where the inner shell of the drier has simply been pivoted within the outer shell, as in prior art driers, such pivotal connections merely allowed the inner shell to creep longitudinally relative to the outer shell under expansion and contraction changes. No particular provision was made for opposing or otherwise compensating for such longitudinal movement, nor for compensating for the radial expansion and contraction movement of the inner shell relative to the outer shell, which radial movement if uncompensated for is equally as disastrous as uncompensated for longitudinal movement.

25 According to our invention, we compensate for both longitudinal and radial expansion and contraction movements of the mandrel relative to the outer shell, and in respect to such longitudinal movement we provide that the mandrel shall move in a straight line, rather than in an arc, thus avoiding any tendency to distort either the mandrel or the shell.

30 In our construction, moreover, the mandrel supporting means is so constructed as effec-

tively to seal the outer shell at all times against the exit therefrom of any part of the material being dried at the points of support.

These, and various other advantages of 55 structure, operation and assembly, are all secured in the drier of the present invention. In the accompanying drawings, we have illustrated one characteristic embodiment of our invention which we have found highly satisfactory in use and well adapted to the requirements of manufacture.

In the drawings:—

Fig. 1 is a side elevation of a drier in accordance with our present invention.

Fig. 2 is a fragmentary longitudinal section thereof.

Fig. 3 is a cross section on the line 3—3 of Fig. 2, and

Fig. 4 is a detail dis-assembly of one of 70 the compensating members, removed.

We have indicated at 1 an outer rotary shell and at 2 an internal hollow core or hot mandrel, which preferably extends the full length of the shell and rotates therewith. The drying heat may be projected into the firing end of the mandrel from any suitable heat source, as the burner B, and the space S between the mandrel and shell constitutes an open-ended drying chamber within which the material to be dried is introduced at the firing end of the drier and from which it is discharged at the opposite end.

For convenience of manufacture, shipment and assembly, as well as replacement or substitution of parts, both shell and mandrel are preferably made in sections, such sections being flanged at their meeting ends to permit them to be bolted to each other in endwise assembly.

The drier as a unit is supported, preferably at a slight inclination to the horizontal, on any suitable supports, and is driven in any suitable manner. For this purpose, each shell section may have one or more circumferential tires 3 adapted to run on suitable rollers 4 on the drier supports. These latter may be simple trestles or bases 5 and 6, one of which is provided with end thrust rolls 7 to 100

take up any end thrust resulting from the inclined position of the drier.

The bases 5 and 6 are capable of being up-ended to serve as wheeled trucks on which 5 the drier may be transported from place to place in the drying room or elsewhere, the rollers 4 in such use functioning as ground wheels.

The use of such bases moreover makes possible a direct drive for the drier. In such 10 case, one of the bases serves as a mount for an electric motor M, the shaft 8 of which has a sprocket 9 which through a chain 10 drives a sprocket 11 on the shell 1. Obviously, of course, other forms of drive, whether 15 direct or indirect, may be employed.

The mandrel sections are telescopically fitted one within the other, and the entire 20 mandrel assembly is so mounted within the shell as not only to rotate in unison therewith but also that both its longitudinal and its radial expanding and contracting movements shall be compensated for.

To this end, the means by which the mandrel is suspended within the shell are constructed both as motion transmitting connections which transmit the rotary effect of the shell to the mandrel so that both shell and mandrel rotate in unison and as compensating devices for taking up the expansion and contraction movements of the mandrel in either a longitudinal or a radial direction.

This result is accomplished by the use of 35 the special mandrel supporting means detailed in Fig. 4. In practice, sets of four spring suspension rods, indicated generally at 12 are preferably used, although our invention is not limited to this or any other 40 number of rods. These rods are disposed radially of the drier in equi-distantly spaced relation. At their inner ends, each rod is hinged to the mandrel. This may be done by means of a continuous band or collar 13 45 encircling the mandrel and fixed thereto in any suitable manner, such band being formed at suitable intervals with a plurality of outwardly projecting ear pairs 14 between which the inner ends of the rods 12 are hinged as 50 at 15, or the band may be an interrupted band, in which event it would present four spaced aligned segments each having a pair of ears to receive the inner ends of the rods 12.

In either case, the hinges thus provided 55 allow the inner ends a pivoting movement as indicated in dotted lines Fig. 2 to compensate for expanding and contracting movements of the mandrel longitudinally relative to the shell.

60 At their outer ends, each rod extends through and beyond the shell, and has a ball and socket connection with the shell permissive of the angular deflection of the rod, as indicated by the dotted line showing of 65 Fig. 2. Such construction includes for each

rod a socket flange 16 through which the rod extends centrally. Each flange 16 is fastened as at 17 to the outer face of the shell and is formed with an outwardly facing cupped socket 18 adapted to receive a packing retainer 18', a packing 19 and a ball spring seat 20, all assembled on the rod in the order named. Seated on the ball spring seat 20 and held on the outer threaded end 21 of the rod 12 by a nut 22 and washer 22' is a coil spring 23.

By means of this construction expansion and contraction movements of the mandrel either longitudinally or radially are compensated for. In the longitudinal movements, the hinge pins 15 move in a straight line rather than an arc, the ball and socket joint afforded by the spring seat 20 and socket flange 16 permitting the rod to swivel relative to the shell, compression or extension of the spring allowing the mandrel to move forwardly or rearwardly in a straight line, with consequent avoidance of any tendency to distort either the shell or mandrel. Moreover, the packing 19 provides an effective seal for the shell at the holes therein through which the rods 12 pass, thus preventing outward leakage from the shell of the material being dried, and this seal is maintained as tight as desired by the spring 95 23 which when set up compresses the packing between the packing retainer 18 and the spring seat 20.

By varying the degree of tightening of the nut 22 on the spring, the tension of the 100 spring may be varied and adjusted to the come-and-go of the mandrel either longitudinally or radially.

Various modifications in the construction and operation of our device may obviously be resorted to if within the spirit and scope of our invention without departing from the limits of the appended claims.

What we therefore claim and desire to secure by Letters Patent is:

1. In a drier, spaced inner and outer shells, suspension members connecting said shells, said members hinged at their inner ends to the inner shell and having ball and socket connection at their outer ends with said outer shell.

2. In a drier, spaced inner and outer shells, suspension members connecting said shells, said members hinged at their inner ends to the inner shell and having ball and socket connection at their outer ends with said outer shell, and exterior means tensioning said suspension members for automatically taking up the radial and longitudinal expansion and contraction movements of the inner shell relative to the outer shell.

3. In a drier, spaced inner and outer shells, suspension members connecting said shell, said members hinged to said inner shell and having ball and socket connection at their 130

outer ends with said outer shell, springs applied to said suspension members beyond said ball and socket connections, and exterior means for adjusting the tension of said springs.

5 4. In a drier, spaced inner and outer shells, rods set through said outer shell and hinged at their inner ends to said inner shell, socket flanges fastened to said outer shell exteriorly thereof, ball spring seats assembled on said rods beyond said socket flanges, springs assembled on said rods beyond said seats, and means for adjusting the tension of said springs.

10 5. In a drier, spaced inner and outer shells, rods set through said outer shell and hinged at their inner ends to said inner shell, socket flanges fastened to said outer shell exteriorly thereof, said flanges pierced to receive said rods and each provided with an outwardly facing cupped socket, a packing and a rounded spring seat assembled on each rod and compressively fitted within a flange socket, said packing sealing the opening in the socket flange through which the rod passes whereby to prevent leakage therethrough of the material being dried from the outer shell, a spring assembled on each rod beyond the spring seat, and means for adjusting the tension of said springs.

15 6. In a drier, spaced inner and outer shells, means for heating one of said shells, and means mounting said inner shell within said outer shell and automatically effective to take up both the radial and the longitudinal expansion and contraction movements of the inner shell relative to the outer shell, said means including rods hinged at their inner ends to said inner shell and having ball and socket connection at their outer ends with said outer shell.

20 In testimony whereof we affix our signatures.
